CLAIM

The ornamental design for a lens for camera, as shown and described.

DESCRIPTION

FIG. 1 is a front, right perspective view of a lens for camera showing the new design;

FIG. 2 is a rear, left perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

1 Claim, 8 Drawing Sheets
